FIG. 7

FIG. 9

FIG. 10

FIG. 11

FIG. 12

FIG. 1 is a three-quarters perspective view, taken from the front and right side of one chair embodying the inventive design;

FIG. 2 is a three-quarters perspective view, taken from the rear and left side, of the chair of FIG. 1;

FIG. 3 is a front elevation view of the chair of FIG. 1;

FIG. 4 is a rear elevation view of the chair of FIG. 1;

FIG. 5 is a right side elevation view of the chair of FIG. 1, the left side elevation view being a mirror image;

FIG. 6 is a plan view of the chair of FIG. 1;

FIG. 7 is a three-quarter perspective view taken from the front and right side of a modified form of the chair shown in FIG. 1;

FIG. 8 is a three-quarters perspective view, taken from the rear and left side, of the chair in FIG. 7;

FIG. 9 is a front elevation view of the chair of FIG. 7;

FIG. 10 is a rear elevation view of the chair of FIG. 7;

FIG. 11 is a right side elevation view of the chair of FIG. 7, the left side elevation view being a mirror image; and

FIG. 12 is a plan view of the chair of FIG. 7.

I claim:

The ornamental design for a chair, as shown and described.
